UNITED STATES PATENT OFFICE.

HAROLD HOLLAND, OF LYNN, MASSACHUSETTS.

WHEEL-RUNNER.

SPECIFICATION forming part of Letters Patent No. 272,691, dated February 20, 1883.

Application filed November 23, 1882. (No model.)

To all whom it may concern:

Be it known that I, HAROLD HOLLAND, of Lynn, in the county of Essex, State of Massachusetts, have invented a certain new and useful Improvement in Wheel-Runners, of which the following is a description sufficiently full, clear, and exact to enable any person skilled in the art or science to which said invention appertains to make and use the same, reference being had to the accompanying drawings, forming a part of this specification, in which—

Figure 1 is a side elevation, and Fig. 2 an end or front view, representing the improvement in use.

Like letters of reference indicate corresponding parts in the different figures of the drawings.

My invention relates to that class of wheel-runners which are employed in converting wheeled vehicles into sleighs, or enabling them to be used when the ground is covered with snow; and it consists in a novel construction and arrangement of the parts, as hereinafter more fully set forth and claimed, by which a simpler, cheaper, and more effective device of this character is produced than is now in ordinary use.

The nature and operation of the improvement will be readily understood by all conversant with such matters from the following explanation, its extreme simplicity rendering an elaborate description unnecessary.

In the drawings, A represents the wheel, and B the runner. The wheel is of ordinary construction, and, being substantially like all of the others belonging to the vehicle for which it is designed, it is deemed essential to show but one. The runner consists of the body C, which is bent upward to form a goose-neck, d, at either end, and provided with the vertically-

arranged standards or braces m m. The body is also provided with upwardly-projecting flanges x for receiving and preventing the wheel from slipping from the runner, and with a shoe, G, attached thereto by the nuts and bolts f; but the shoe may be omitted, if desired. Two U-shaped clamps, J J, are employed for attaching the runner to the wheel, the clamps passing around the felloes of the wheel and being secured by the nuts l, as seen in Fig. 1.

As all wheels are not of the same size, in securing the runner it is sometimes necessary to bend the necks d inwardly in order to connect them with the clamps J, thereby tending to curve or bend the bottom or shoe and render the runner less perfect in its operations. The standards or braces m are designed to obviate this difficulty, and in that respect they form an important feature of my invention, serving to keep the runner straight on its bearing-surface.

Having thus explained my invention, what I claim is—

The improved wheel-runner described, the same consisting of the body C, having the goose-necks d d, provided with the U-shaped clamps J J for attaching the same to the wheel, the shoe G, provided with the nuts and bolts f for attaching the same to the body, the flanges x for preventing the wheel from slipping laterally from the runner, and the two vertical braces m m, arranged equidistant from the flanges x, to strengthen and prevent the runner from bending, all being constructed, combined, and arranged to operate substantially as specified.

HAROLD HOLLAND.
